DESIGN FOR A FISHING ROD AND REEL

George R. Hauser and George Hauser,
Garfield Heights, Ohio

Application October 14, 1946, Serial No. 133,936

Term of patent 14 years

(Cl. D31—4)

To all whom it may concern:

Be it known that we, George R. Hauser and George Hauser, citizens of the United States, and residents of the city of Garfield Heights, State of Ohio, have invented a new, original, and ornamental Design for a Fishing Rod and Reel, of which the following is a specification, reference being had to the accompanying drawing, forming a part thereof.

Figure 1 is a side view of a fishing rod and reel, showing our new design; and,

Figure 2 is a top plan view.

The characteristic features of our design reside in the portions shown in full lines.

We claim:

The ornamental design for a fishing rod and reel, substantially as shown and described.

GEORGE R. HAUSER.
GEORGE HAUSER.
